UNITED STATES PATENT OFFICE.

CARL GABRIELSON, OF SYRACUSE, NEW YORK, AND WILLIAM H. STEARNS, OF WORCESTER, MASSACHUSETTS, ASSIGNEES TO L. C. SMITH & BROS. TYPEWRITER COMPANY, OF SYRACUSE, NEW YORK, A CORPORATION OF NEW YORK.

TYPE-BAR CUSHION.

No. 892,043.

Specification of Letters Patent.

Patented June 30, 1908.

Application filed July 11, 1904. Serial No. 216,352.

To all whom it may concern:

Be it known that we, CARL GABRIELSON and WILLIAM H. STEARNS, citizens of the United States, and residents, respectively, of 5 Syracuse, Onondaga county, State of New York, and Worcester, Worcester county, State of Massachusetts, have invented certain new and useful Improvements in Type-Bar Cushions, of which the following is a 10 specification.

This invention comprises a type-bar cushion or pad for typewriting machines adapted to normally support the free ends of the type-bars and to cushion and deaden the 15 sound produced by the type-bar as it drops back from the platen.

The present invention relates to a cushion of peculiar structure which is sufficiently inelastic to prevent any material rebounding 20 of the type-bar and which is soft enough to prevent any injury to the type-bar or any considerable noise due to the impact of the type-bar.

The invention will be described in detail 25 in connection with the accompanying drawing, in which,

Figure 1 is a side view of a type-bar cushion and its support; Fig. 2 is a section of the same on the line 2—2 of Fig. 1 and 30 showing a type-bar in side elevation; Fig. 3 is a vertical longitudinal section of the cushion; Fig. 4 is a transverse section of the cushion; and Fig. 5 is a similar section showing a modification.

35 Referring to the drawing, *a* indicates a type-bar cushion, *1* the support therefor, *2* a type-bar and *3* its hanger. The support *1* may be of any suitable construction and its form is immaterial so far as the present invention is concerned. The character of the machine, whether the same be a front-strike 40 machine or otherwise, is also immaterial.

The cushion *a* comprises a series of consecutive superposed layers *4* of fabric prefer- 45 ably covered by an envelop or jacket *5*. The

cushion shown in Figs. 3 and 4 consists of a series of strips laid one on the other, said strips being filled or saturated with viscous material which causes them to adhere more or less and also destroys or decreases the 50 natural elasticity of the fabric. In practice it has been found that the adhesive tape used by electricians when arranged in layers, as shown in the drawing, forms a very effective cushion. The adhesive properties of the 55 tape serve to hold the layers of fabric in proper relative position, but non-adhesive viscous material may be used with good results. The saturating material should be of a kind which will not evaporate readily, and 60 to prevent drying out and also to form a suitable finish for the pad, it is covered by an envelop *5* which is preferably constructed of some tough air and water proof fabric. As shown in Fig. 4 the envelop consists of a strip 65 having its edges united at *6* by sewing or otherwise.

In Fig. 5 there is shown a pad made up of a single piece of fabric *7* folded upon itself back and forth to form a cushion of the desired 70 depth. This cushion is surrounded by a continuous envelop *8*.

It is well known that the speed with which a typewriting machine may be operated depends somewhat upon the effectiveness of 75 the pad for preventing rebound of the type-bar. If the pad be elastic the bar would require some time to come to rest and if an adjacent bar be operated before it comes to rest the two may collide, causing loss of time and 80 possible injury to the type-bars. The pad herein described has been thoroughly tested and found to be very effective.

It will be evident that the invention is not limited to any particular fabric or to any particular saturating material. It is to be understood however that in the preferred form of our invention we use a series of layers of fabric treated with adhesive material, which cohere and form a solid pad. 85 90

Having described our invention what we desire to secure by Letters Patent is,

1. A type-bar pad comprising a series of superposed layers of textile fabric having viscous material incorporated therewith, and an inclosing envelop of substantially air and waterproof material.
2. A type-bar pad comprising a series of superposed layers of textile fabric having adhesive and viscous material incorporated therewith, and an envelop surrounding and inclosing said layers.

In testimony whereof we have signed our names to this specification in the presence of two subscribing witnesses.

CARL GABRIELSON.
WILLIAM H. STEARNS.
